Primary Examiner—Stella Reid*Assistant Examiner*—Mark Goodwin(74) *Attorney, Agent, or Firm*—Buchanan Ingersoll & Rooney PC(57) **CLAIM**

The ornamental design for a multiple container pack, as shown and described.

DESCRIPTION

FIG. 1 is a bottom plan view of a multiple container pack showing my new design.

FIG. 2 is a top plan view thereof.

FIG. 3 is a side elevational view, the other side being a mirror image thereof.

FIG. 4 is a front elevational view, the rear being a mirror image thereof.

FIG. 5 is a top, front and side perspective view thereof; and, FIG. 6 is a bottom, rear and side perspective view thereof. The broken line showing of the stylized logo in FIGS. 3-6 is for illustrative purposes only and forms no part of the claimed design.
